MISSILE BOOSTER

Stanley Lehrer, Pompton Lakes, N.J., assignor to Thiokol
Chemical Corporation, Bristol, Pa., a corporation of
Delaware

Filed Feb. 17, 1961, Ser. No. 63,969

Term of patent 14 years

(Cl. D71—1)

Fig. 1

Fig. 2

Fig. 3

Fig. 4

Fig. 5

FIGURE 1 is a side elevation of a missile booster showing my new design, all sides thereof being the same in appearance as indicated in FIGURE 2;

FIGURE 2 is a cross-sectional view thereof taken on the line 2—2 of FIGURE 1 in the direction of the arrows;

FIGURE 3 is a bottom plan view of the missile booster;

FIGURE 4 is an enlarged fragmentary perspective view illustrating, in detail several of the rocket motors arranged around the circumference of the missile booster as shown in FIGURE 1; and

FIGURE 5 is a vertical cross-section through one of the rocket motors on the enlarged scale shown in FIGURE 3.

The dominant features of my design reside in the portions shown in full lines.

I claim:

The ornamental design for a missile booster, as shown and described.
